UNITED STATES PATENT OFFICE.

JOSEPH J. SOLDAT, OF CHICAGO, ILLINOIS, ASSIGNOR TO THE BEARDSLEY & PIPER COMPANY, OF CHICAGO, ILLINOIS, A CORPORATION OF ILLINOIS.

MOLDING MACHINE.

Application filed August 27, 1923. Serial No. 659,539.

To all whom it may concern:

Be it known that I, JOSEPH J. SOLDAT, a citizen of the United States, and a resident of Chicago, in the county of Cook and State 5 of Illinois, have invented certain new and useful Improvements in Molding Machines, of which the following is a full, clear, and exact description.

The invention relates to molding machines. In the operation of molding machines of the type exemplified in Letters Patent No. 1,335,642 and No. 1,408,493, to Beardsley and Piper an endless belt carried by the swinging projector supporting arm 15 is used to deliver sand into the projector casing. The primary object of the present invention is to provide an improved construction in which the maximum carrying capacity of the belt is attained, so that a 20 belt of minimum width will suffice to deliver sand in sufficient quantity to the projector. In machines of this type, it is desirable to avoid excessive weight in the carrying belt, because of the necessity of manually shifting 25 it with the arm in sling sand into all portions of a flask in making molds.

The invention consists in the several novel features hereinafter set forth and more particularly defined by claims at the conclusion 30 hereof.

In the drawings: Fig. 1 is a side elevation of a molding machine embodying the invention. Fig. 2 is a longitudinal section through the projector and its supporting 35 arm. Fig. 3 is a transverse section on line 3—3 of Fig. 1. Fig. 4 is a plan.

The invention is exemplified in a machine comprising a column 10; a jib 13 provided with a socket 11 pivoted to swing horizontally 40 over a flange 12 on the column; and a horizontally movable arm 18 which supports the sand projector and has a spindle 17 at its inner end which is suitably journaled in a socket 14 fixed to the outer end of 45 jib 13. This arm comprises a casing 15 secured by bolts 16 to a flange on the top of spindle 17 and a tube 18' which has its inner end secured in casing 15 and supports the sand projector at its outer end. The projector 50 comprises a head 20, on which is secured a projector blade 21 with a cut-off blade 22 at one side, and a casing 23 which co-operates with the blade 21 in slinging the

sand into a flask beneath the projector. The projector casing is secured by a yoke 24 to 55 the tube 18'.

An electric motor 26 is bolted to one end of casing 15 and the shaft of said motor extends through said casing and tube 18 and projects beyond the outer end of said tube. 60 The projector-head 20 is journaled on roller-bearings 28 around tube 18' and is fixed to the outer end of shaft 27 by a collar 33 which is keyed to the shaft and bolted to 65 said head, to cause the projector blade to be driven at a high speed. The purpose, in providing an arm and a jib to support the projector, is to permit the latter to be moved 70 horizontally to sling sand into all portions of a flask.

The mechanism for feeding sand to the projector comprises an inclined chute 40 which contains a riddle 60 and is supported over jib 13 and an endless belt 41 supported over and movable with the supporting arm 18. Chute 40 delivers the sand into a hopper 42 which is supported by and movable with arm 18 and guides the sand onto belt 41. The latter delivers sand through an open side 43 into the projector casing 23. Conveyor 40 is supported so that it can be vibrated by suitable mechanism comprising 75 an electric motor and gearing in a case 48 which is mounted to swing with jib 13. This mechanism may be of the construction 80 set forth in Patent No. 1,408,493.

The mechanism for driving the conveyor belt 41 comprises a bevelled pinion 61 which is keyed to shaft 27 in the casing 15; a bevelled gear 62 meshing with pinion 61 and 85 fixed to a transverse shaft 63 which is mounted in a bearing 65 in the casing; a pinion 66 fixed to shaft 63; an idler-gear 67 on a stud shaft 68 and meshing with pinion 66; and a gear 69 fixed to the hub 90 70 of a pulley 71 around which the belt 41 passes and by which it is driven. Pulley 71 is rotatably supported by a stationary shaft which is suitably supported by the casing 15. This mechanism may also be 95 of the construction set forth in Patent No. 1,408,493. The outer end of belt 41 is supported and guided by an idler pulley 87 which is rotatably supported by a shaft 88 100 which is secured in bearings 89 on yoke 24. 105

The belt 41 is operated at a rather high

speed, and in order to increase its carrying capacity by providing means for supporting its margins between its supporting rollers and preventing sand from falling off the belt laterally, an angle iron bar 50 is provided at each side of the belt. Each bar 50 has a horizontal flange 51 underlying and supporting one side margin of the belt and a vertical flange 52 which prevents the sand from falling laterally off the belt. The inner ends of bars 50 are connected by a semi-circular portion 53. The bottom flanges 51 of bars 50 terminate at 51^a below the connecting portion 53, so that the belt will pass from its pulley 71 onto the flanges 51 and so that the latter will support the belt vertically and prevent its sagging between pulleys 71 and 87. The lower margins of hopper 42 lap and are riveted to the vertical flanges of bars 50. A supporting plate 55 has its lower end suitably secured to gear-casing 15 and its upper end is riveted to the connecting portion 53. The inner end of the hopper is reinforced by a strip 56 which is riveted thereto and to plate 55. Plate 55 serves as a support for the hopper 42 and the bars 50. The outer ends of bars 50 are supported by a cross-bar 57 which extends under the horizontal flanges 51 of bars 50 which are removably held on the bar 57 by hook lugs 58 which are riveted to flanges 50. Cross bar 57 is supported by rods 59 which have their lower ends fixed in a supporting clamp 59 which is secured on tube 18. The outer ends of bars 50 terminate adjacent pulley 87 where the bottom flanges 51 are cut away, as at 51', and the projecting vertical flanges 52' are bent inwardly to constrict the stream of sand as it is leaving the belt so that it will pass into the projector casing. The outer ends of bars 50 are secured in properly spaced relation by a rod 45 which extends through plates 46 which are riveted to the vertical flanges 52 of said bars and are provided with nuts 47 for clamping the plates on said rod.

The invention exemplifies a molding machine of the sand projector type in which an endless belt is used to convey sand to the projector and in which the margins of the belt are supported to prevent it from sagging between the pulleys and in which the bars are provided with flanges for retaining the sand on the belt. As a result of this construction, a belt of minimum size and weight may be used for delivering the sand to the projector; the margins of the belt are supported to prevent it from sagging between its supporting pulleys and the vertical flanges of the angle iron retain the sand on the belt. This construction is of special importance in a machine in which the belt is mounted on a manually operated laterally swinging projector carrying arm.

The invention is not to be understood as restricted to the details set forth, since these may be modified within the scope of the appended claims without departing from the spirit and scope of the invention.

Having thus described the invention, what I claim as new and desire to secure by Letters Patent, is:

1. In a molding machine, the combination of a sand projector, means to movably support the projector, and means to deliver sand to the projector comprising an endless belt, pulleys for the belt, and longitudinal bars underlying and supporting the margins of the belt between the pulleys.

2. In a molding machine, the combination of a projector, means to movably support the projector, and means to deliver sand to the projector comprising an endless belt, pulleys for the belt, and longitudinal bars underlying and supporting the margins of the belt between the pulleys and provided with vertical members to retain the sand on the belt.

3. In a molding machine, the combination of a sand projector, means to deliver sand to the projector comprising an endless belt, and pulleys for the belt, longitudinal bars underlying and supporting the margins of the belt between the pulleys, and a pivoted arm on which the belt, pulleys and bars are supported.

4. In a molding machine, the combination of a pivoted arm, a sand-projector supported on said arm, mechanism to drive the projector mounted on said arm, an endless belt supported on and movable with said arm for feeding sand to the projector, pulleys for the belt and bars supported on the arm and underlying and supporting the margins of the belt between the pulleys.

5. In a molding machine, the combination of a pivoted arm, a sand projector supported on said arm, mechanism to drive the projector mounted on said arm, an endless belt supported on and movable with said arm for feeding sand to the projector, pulleys for the belt and bars longitudinally supported on said arm and underlying and supporting the margins of the belt between the pulleys and provided with members to retain the sand on the belt.

6. In a molding machine, the combination of a movable sand projector, a motor movable with and for driving the projector, an endless belt for feeding sand to the projector, driving means and pulleys for the belt, and longitudinally extending angle-bars having horizontal flanges underlying and supporting the margins of the belt.

7. In a molding machine, the combination of a movable sand projector, a motor movable with and for driving the projector, an endless belt for feeding sand to the projector, driving means and pulleys for the belt, and longitudinally extending angle

- bars having horizontal flanges underlying and supporting the margins of the belt, and upstanding vertical flanges to hold the sand on the belt.
- 5 8. In a molding machine, the combination of a movable sand projector, a motor movable with and for driving the projector, an endless belt for feeding sand to the projector, driving means and pulleys for the belt, 10 longitudinally extending angle-bars having horizontal flanges underlying and supporting the margins of the belt and upstanding vertical flanges, and a hopper secured to one end of said bars.
- 15 9. In a molding machine, the combination of an arm, a projector supported on one end of said arm, a motor for driving the projector movable with the arm, an endless belt for feeding sand to the projector, mounted 20 on and movable with said arm and projector, driving means and pulleys for the belt mounted on said arm, and longitudinally extending angle-bars supported on the arm and having horizontal flanges underlying 25 and supporting the margins of the belt, and upstanding vertical flanges to hold the sand on the belt.
10. In a molding machine, the combination of an arm, a projector supported on one end of said arm, a motor for driving the projector movable with the arm, an endless belt for feeding sand to the projector, mounted on and movable with said arm and projector, driving means and pulleys for the
- belt mounted on said arm, longitudinally extending angle-bars supported on the arm and having horizontal flanges underlying and supporting the margins of the belt, and upstanding vertical flanges to hold the sand on the belt, and a hopper secured to one end 40 of said bars.
11. In a molding machine, the combination of a projector, means to movably support the projector, and means to deliver sand to the projector comprising an endless belt, 45 pulleys for the belt, and longitudinally extending bars having flanges underlying and supporting the marginal portions of the belt and vertical flanges for retaining the sand on the belt and having their outer ends shaped 50 to constrict the stream of sand as it enters the projector.
12. In a molding machine, the combination of a sand projector, a pivoted arm to movably support the projector and means 55 mounted to swing with said arm to deliver sand to the projector comprising an endless belt, pulleys for the belt, and longitudinally extending bars having flanges underlying and supporting the marginal portions of the 60 belt and vertical flanges for retaining the sand on the belt, and having their outer ends shaped to constrict the stream of sand as it enters the projector.

Signed at Chicago, Illinois, this 31st day 65 of July, 1923.

JOSEPH J. SOLDAT.
